UNITED STATES PATENT OFFICE.

WILLIAM TUNSTILL, OF NEW YORK, N. Y.

MACHINE FOR DRILLING METAL.

SPECIFICATION forming part of Letters Patent No. 248,812, dated October 25, 1881.

Application filed May 18, 1881. (No model.)

To all whom it may concern:

Be it known that I, WILLIAM TUNSTILL, of the city and State of New York, have invented an Improvement in Drilling-Machines, of which 5 the following is a specification.

Drilling-machines have been made with a frame that carries the drilling mechanism capable of being inclined, so that the drilling can be effected at an inclination to the bed or 10 support for the article operated upon.

My invention relates to a drilling-machine that is adapted to hand use, and in which the standard that carries the drill can be inclined, and the bed upon which the article to be drilled 15 rests can be inclined and moved to carry such article up to the tool.

In the drawings, Figure 1 is a side elevation of my improved drilling-machine, and by dotted lines the drilling mechanism is shown in 20 an inclined position. Fig. 2 is a front elevation of the machine. Fig. 3 is an elevation showing a modification of the arm that supports the drilling-tool, and Fig. 4 is a plan of such arm.

25 The bed *k*, upon which the article to be drilled rests, is provided with a central shaft, *k'*, that passes through bearings in the carrier *l*, and this bed and shaft can be revolved, if desired, in their bearings. The carrier *l* is between two 30 vertical frames, *b'*, that are cast upon or bolted to the base-plate *a*; and *m* is a pivot-bolt passing through the frames *b'* and through the carrier *l*, and upon this pivot the carrier and bed can be swung, so that the bed will be either 35 horizontal or at an inclination.

In the vertical frames *b'* there are segmental slots, and the bolt *n* passes through these segmental slots and through the carrier *l*, so that the parts can be clamped firmly in place by 40 this bolt *n* when the bed has been properly placed in presenting the article upon the bed *k* to the drill, hereinafter described. The carrier *l* is L-shaped, the vertical part being parallel with the shaft *k'* and the horizontal part projecting beyond the edges of the frames *b'*, and 45 the shaft *k'* can be moved endwise in its bearings in said carrier *l*, and there is a pivot-bearing beneath the horizontal part of this carrier *l* for the pivot *p'* of the lever *p*, and the short 50 end of this lever is against the lower end of

the shaft *k'*, so that power can be applied to move said shaft *k'* endwise, and the bed, with the article to be drilled, toward the drill, and for this purpose a movable weight, *r*, may be applied to the lever *p* as a counterpoise to the 55 bed and the article upon it.

The segmental flanges *b* are cast with or bolted to the base-plate *a*, and between them is the foot of the standard *e*.

d is a pivot-bolt passing through the flanges 60 *b* and standard *e*, and upon this bolt the standard can be swung, while *e* is a clamping-bolt 65 passing through the standard and through segmental slots in the flanges *b*, by means of which the parts can be clamped to hold the 70 standard vertically or at an inclination. The dotted lines in Fig. 1 show the standard as inclined. The upperend of the standard *e* is round, and passes through an eye at the end of the arm *g*, and *h* is a set-screw by means of which the 75 arm is held firmly to the standard. This allows the arm and drilling mechanism to be raised or lowered upon the standard, or to be turned around horizontally to a greater or less extent, and thereby bring the drill to the desired place upon the article to be drilled.

The drill *t* and the chuck *u* holding the same are to be of any desired character.

The arbor 10 for the drill is provided with a pinion, *w*, and *v* is a gear-wheel upon a horizontal stud or gudgeon, and a crank or hand wheel, *s*, is employed for rotating the wheel *v*, pinion *w*, arbor 10, and drill.

In Figs. 1 and 2 the arm *g* is shown as adapted to receive and clamp a drill-stock, *i*, with a 85 breast-piece at the upper end, and in Figs. 3 and 4 the drill-stock and breast-piece are dispensed with.

The means for holding the drill-arbor and rotating the drill-chuck and drill by hand, and 90 the devices for supporting and adjusting the article to be drilled, enable the workman to operate the drilling mechanism with facility.

I claim as my invention—

1. The combination, in a drilling-machine, of 95 the bed *k*, shaft *k'*, pivoted carrier *l*, clamping-bolt *n*, slotted frames *b'*, and lever *p*, substantially as set forth.
2. The combination, in a drilling-machine, of 100 the standard *e*, segmental flanges *b*, pivot-bolt *d*,

d, clamping-bolt *e*, movable arm *g*, clamping-screw *h*, drill, gearing, and crank for actuating the drill, substantially as set forth.

3. The combination, in a drilling-machine, of a standard pivoted at the lower end, and means for holding the same either vertically or at an inclination, the arm *g* and drilling mechanism, the bed *k*, pivoted carrier, supporting and

clamping mechanism, and the lever *p* for moving the bed toward the drill, as set forth.

Signed by me this 16th day of May, A. D. 1881.

W. TUNSTILL.
